UNITED STATES PATENT OFFICE.

FRANK S. LEWIS, OF DENVER, COLORADO.

ARCH SUPPORT.

Application filed January 4, 1922. Serial No. 526,923.

To all whom it may concern:

Be it known that FRANK S. LEWIS, a citizen of the United States of America, residing at Denver, in the county of Denver and State of Colorado, has invented new and useful Improvements in Arch Supports, of which the following is a specification.

The object of the invention is to provide a relatively simple and efficient foot arch support for remedying or relieving broken down or flattened foot arches and particularly to provide a device of this type wherein adjustment may be made to adapt the device to different conditions of the foot and varying degrees of development of the disability involved; and with these objects in view the invention consists in a construction and combination of parts of which a preferred embodiment is shown in the accompanying drawings, wherein:

Figure 1 is a view of the support in its normal position with the containing shoe indicated in dotted lines with reference thereto.

Figure 2 is an inverted plan view of the support.

Figure 3 is a longitudinal sectional view of the same with the parts in the normal position.

Figure 4 is a similar view with the arch depressed to the limit of movement permitted by the restraining element.

Figure 5 is a transverse sectional view.

Figure 6 is a detail view of the transverse plate.

Figure 7 is a detail section on the plane indicated by the line 7—7 of Figure 2 to show the means of attachment of the heel corrector.

Figure 8 is a detail view detached of the metatarsal corrector.

Figures 9 and 10 are detail views of modified forms of limiting or retaining strips or members.

The shell or body portion 10 of the support is of transversely concaved and longitudinally arched form affording heel and toe bearing portions 11 and 12, and arranged in contact with the under surface thereof is a transverse reinforcing plate 14 having upturned terminals of which that at the outer side of the foot is preferably bifurcated to form tongues 15. This transverse contracting member which is of spring metal permitting it to yield to allow a limited lateral spreading of the foot while affording a sub-

stantial resistance thereto, is carried by a main or arch spring plate 16 disposed longitudinally of the shell or body member, being terminally attached thereto by rivets 17 and 60 being arched in form to reinforce the shell which though of relatively stiff leather is adapted to yield or flatten to a certain extent. In order to limit the extent of flattening of the main spring plate and hence of 65 the shell under the weight of the wearer, while permitting a sufficient yielding of the same to cushion the foot there is employed a retaining or limiting member 18 terminally connected with headed studs 19 70 on the under side of the plate and serving, when the plate reaches the prescribed limit of flexion to assume a position of a chord of the segment described by the spring plate and thus prevent further flattening of the 75 latter. The permissible or tensionable limit of flexure of the arch 16 varies in different cases or with different patients and therefore in order to permit of an adjustment adapting the amount of flattening movement 80 to be varied as required, the limiting or retainer member 18 may be replaced by another of a different length or as preferred and as indicated in Fig. 9 may be of triangular form provided adjacent the shorter base 85 of the triangle with a transverse series of keyhole slots 20 of which each succeeding one is slightly closer the adjacent end than the next succeeding so as to dispose these slots at different distances from a similar 90 keyhole slot 21 at the apex of the triangle. The slots 20 are obviously selectively engageable with the adjacent stud 19 to suit the desired purpose. A modified form of limiting member is illustrated in Figure 10, 95 this being provided with heart-shaped openings 20^a and 21^a at opposite ends, the branch recesses 20^b and 20^c of the opening 20^a being at different distances from the adjacent extremity of the member, while the branch recesses of the opening 21^a are the same distance from the adjacent extremity of the member. Obviously the studs 19 may be engaged in either branch recess 20^b or 20^c of the opening 20^a and the corresponding recess of the opposite opening 21^a in order to 100 vary the operative length of the retaining members.

The transverse reinforcing or contracting plate is carried by the main or longitudinal 110 spring plate 16 for which purpose a rivet 22 is employed, and in order that the said

- transverse plate may be adjusted longitudinally of the shell and hence of the foot of the wearer to accommodate long and short heels and afford the proper support and protection for the cuboid on the outside and the scaphoid on the inside of the foot it is slotted as indicated at 23, longitudinally of the support to permit of forward and rearward movement or adjustment.
- 10 At the heel end of the shell there is provided a heel corrector consisting of a pad 24 interposed between inner and outer or upper and lower leaves 25 and 26 of the shell and secured by a rivet 27, while at the toe portion of the shell there is employed a metatarsal corrector consisting of a pad 28 secured by rivets 29. It will be obvious that different thicknesses of pads may be used in either of these relations to wit for heel and metatarsal correction or the removal thereof may be effected when such correction is unnecessary.
- Having described the invention, what is claimed as new and useful is:—
- 25 1. A foot arch support having a shell provided with longitudinal and transverse

spring plates of which the former is upwardly arched to reinforce the shell and the latter terminally upturned to protect the cuboid and scaphoid of the foot, the transverse member having a floating connection with the longitudinal member for adjustment longitudinally of the shell. 30

2. A foot arch support having a shell of limited yielding properties provided with a longitudinally disposed arch spring plate provided on the under-surface with spaced studs, and a triangularly shaped retaining element formed with a keyhole slot adjacent the apex for engagement with one of said studs, and a plurality of keyhole slots disposed adjacent the shorter base and arranged in a series in the direction of the length of said shorter base, each slot of said series being a greater distance from the shorter base than the preceding slot for selective engagement with the remaining stud to vary the limit of flexion of the plate. 35

40 In testimony whereof he affixes his signature.
